UNITED STATES PATENT OFFICE.

EDWARD M. LOCKWOOD, JR., OF DARBY, PENNSYLVANIA, ASSIGNOR TO
EMMA M. TOMSON, MARTIN E. BRIGHAM, AND HARRY K. BUCK, OF PHILA-
DELPHIA, PENNSYLVANIA, COPARTNERS TRADING AS P. C. TOMSON AND
COMPANY, OF PHILADELPHIA, PENNSYLVANIA.

CONVEYER-CHAIN FOR MATCH-MACHINES.

SPECIFICATION forming part of Letters Patent No. 700,433, dated May 20, 1902.

Application filed March 4, 1902. Serial No. 96,879. (No model.)

To all whom it may concern:

Be it known that I, EDWARD M. LOCKWOOD, Jr., of Darby, Delaware county, Pennsylvania, have invented an Improvement in Conveyer-
5 Chains for Match-Making Machines, of which the following is a specification.

My invention has reference to conveyer-chains for match-making machines; and it consists of certain improvements fully set
10 forth in the following specification and shown in the accompanying drawings, which form a part thereof.

The object of my invention is to so construct a conveyer-chain for match-making
15 machines that it shall be light in weight, strong in construction, cheap in cost, and easily repaired when necessary.

My object is also to so form the match-stick-carrying bars which compose the conveyer-chain that they may be stamped by suitable dies from sheet-steel, with the result that they shall be practically unbreakable and absolutely uniform in shape.

My invention in general consists of a conveyer-chain built up of stamped bars having match-stick-carrying sockets. In carrying out my invention I form the conveyer of sections hinged together, each section consisting of a series of transverse compound or composite bars having sockets for supporting the match-sticks and connected to side or rack bars near each end, which unite them and provide means for hinging one such section to the next. The bars are of stamped sheet-
25 steel, and consist of a main perforated bar combined with a supplemental crimped bar provided with a series of semicircular portions driven outward and extended through the perforations or apertures of the main bar
30 to form sockets through which the match-sticks may be thrust and by which they are held and guided upon the bar. The sockets are thus formed without drilling, and as the bar is made by dies every bar is a counter-
35 part of the other, and hence cheapness as well as accuracy of construction is secured. The bars are flanged to secure strength, and the ends projecting beyond the rack-bars consti-

tute sockets or teeth, with which the teeth of the driving sprocket or gear wheels engage 50 for propelling the conveyer as a whole.

My invention also consists of details of construction, all of which will be better understood by reference to the drawings, in which—

Figure 1 is a plan view of a portion of a conveyer-chain, parts being shown in section and dotted lines and also in its relation to the driving sprocket-wheels. Fig. 2 is a front elevation of a portion of same. Fig. 3 is an end view of same. Fig. 4 is a perspective view 60 of a portion of one of the stamped sheet-metal bars making up the conveyer. Fig. 5 is a horizontal section on line 5 5 of Fig. 2, and Fig. 6 is a vertical transverse section on line 6 6 of Fig. 2. 65

A A represent two sections of the conveyer-chain, the entire conveyer being made up of a very large number of such sections connected end to end to form an endless chain. Each section A consists of match-carrying bars D, arranged parallel and connected together by the end rack-bars B, which rack-bars of adjacent sections are hinged at d in any suitable manner. These rack-bars B consist of central body portions having long laterally-projecting lugs C between the hinge ends and short lateral lugs c adjacent to one of the ends. The bars D are substantially U-shaped in cross-section, having the horizontal flanges D'D'. The body portion at the 75 middle is provided with rectangular apertures L and at each end is slotted, as at d, to receive the central or body part of the rack-bars between the projecting lugs C, as shown in Figs. 2 and 3. A supplemental bar 80 N fits to the back of the bar D and is provided with a series of outwardly-extending curved portions I, forced up through the apertures L of the body of the bar D, so as to produce a series of vertical sockets J for the reception of the match-sticks M. The lips of these outwardly-extending portions I are outwardly flared, as at i, though it is perhaps important that said outward flaring should be only on the lower lips or those directed toward the approaching match-sticks. How- 90 95

ever, by having both lips flaring the bars may be inverted, if desired. These bars N are forced into position and retain themselves in place by friction, which is amply sufficient for 5 the purpose. I also prefer to form the body of the bar with recessed guide portions K above and below the apertures and in alignment with the outwardly-projecting portions I, to better guide and hold the match-sticks 10 parallel. As shown in Fig. 5, the bar N intermediate of its loops or projecting portions I locks with the narrow parts l of the bar D intermediate of the apertures L, and hence no thrust of the match-sticks can separate 15 the elements of the bar. To prevent the ends of the sticks catching upon the edge of the metal, the edges k are bent backward, forming rearwardly-flaring lips back of the projecting portion I. In this manner the match- 20 sticks M are guided vertically through the apertures J without danger of catching upon the edges i or k of the composite bar. The ends of these bars D are so shaped as to preferably form rectangular end sockets E, in which the 25 teeth of the driving sprocket-wheels F engage, as shown in Fig. 1, the said sprocket-wheels rotating in a horizontal plane. The rear flanges D of the bars rest against the outer ends of the lugs C, as shown in Fig. 3, 30 and are thus held in steady position upon the rack-bars. The rear bar D of each section is held in position by a spring G, which is sprung into position back of the bar and has its ends bent, as at g, and hooked over the 35 short lugs c of the rack-bars, as shown in Figs. 1 and 3. This spring also holds the rack-bars in place and prevents them spreading toward the outer ends of bars D.

It is seen that the cost of producing the 40 bars D N is much less than bars of cast or forged metal with the holes drilled and also that as the bars are made with dies the position of every hole is definitely fixed. The bars being equally spaced apart, they produce, in effect, racks E at their ends to receive the driving-teeth of the sprocket-wheels F, and thereby obviate the necessity of separate teeth either upon the bars D or upon the 45 rack-bars B. The ends of the bars D are 50 preferably rectangular; but the middle portions may have the corners more or less rounded for more readily guiding the match-sticks. The grooves K and the loops I form three 55 places of support for the match-stick in alignment, and hence the sticks are all held parallel and in true position.

While I prefer to hold the two parts D N of the bar together by their frictional contact, they may be connected in any way desired to make a firm union.

I do not limit myself to the manner of connecting the series of bars D into a section or of connecting the sections, as these and others of the details may be modified or changed 65 as desired; but the construction shown is simple and effective and excellently adapted

to the purpose of this invention. It also permits easy dismantling of the conveyer for repairs, so that very little loss of time is required in the operation of the machine even 70 when repairs are required.

Having now described my invention, what I claim, and desire to secure by Letters Patent, is—

1. A conveyer for a match-machine consisting of longitudinal connecting-links, combined with a series of transverse composite bars secured to the links and each consisting of a bar of stamped sheet metal having a series of apertures, and a second bar of sheet 80 metal having a series of loops arranged through the apertures of the perforated bar to form supports for the match-sticks and in which the loops support the match-sticks on one side and the surfaces on the face of the 85 perforated bar above and below the loops support the match-sticks on the other side.

2. A composite match-stick-supporting bar for a conveyer consisting of a sheet-metal bar having a bent flange for strength and its body 90 formed with a series of apertures, combined with a second sheet-metal bar having a series of outwardly-projecting looped portions pressed through the apertures to form match-stick guides.

3. A composite match-stick-supporting bar for a conveyer consisting of a sheet-metal bar having a bent flange for strength and having its body formed with a series of apertures, combined with a second sheet-metal bar having a series of outwardly-projecting looped portions pressed through the apertures to form match-stick guides I and having their edges flaring outward as at i.

4. A composite match-stick-supporting bar 105 for a conveyer consisting of a sheet-metal bar having a bent flange for strength and having its body formed with a series of apertures and grooves K above and below the apertures, combined with a second metal bar having a 110 series of outwardly-projecting looped portions extending through the apertures to form guides I in line with the grooves K for the match-sticks.

5. A composite match-stick-supporting bar 115 for a conveyer consisting of a sheet-metal bar having a bent flange for strength and its body formed with a series of apertures the upper and lower edges of which flare backward as at k, combined with a second metal bar having a 120 series of outwardly-projecting looped portions extending through the apertures to form match-stick guides.

6. A composite match-stick-supporting bar 125 consisting of a sheet-metal bar having a series of apertures and vertical guiding portions transversely to its length above and below said apertures, combined with a metal strip of less width than the bar and formed with a series of loops and attached to the 130 sheet-metal bar and forming outwardly-projecting looped portions over the apertures and

in line with the guiding portions thereof, whereby the match-stick is properly held and guided.

7. A composite match-stick-supporting bar consisting of a bar having a series of perforations combined with metal looped portions pushed through the apertures to form a series of loops extending from the face of the bar for holding the match-sticks.

10. 8. A composite match-stick-supporting bar consisting of a bar having a series of perforations and vertical guide-grooves in its body above and below the apertures transversely to the length of the bar combined with metal looped portions pushed through the apertures to form a series of loops extending from the face of the bar for holding the match-sticks and in line with the vertical guide-grooves.

9. A match-stick-supporting bar for a conveyor consisting of a channel-bar the intermediate body of which is provided with perforations, combined with a second flat bar bent into a series of projecting portions I extending through the apertures and forming

25 match-stick guide-apertures J bounded on one side by said projecting portions and on the other side by the body of the channel-bar above and below the apertures.

10. In a conveyer for a match-machine, a section comprising the rack-bars B having 30 lugs C c, combined with the composite supporting-bars for the matches having flanges D' apertures L and slots d into which the rack-bars fit and bar N having the loops I extending through the apertures, and in which the 35 flanges D' rest against the lugs C of the said rack-bars.

11. In a conveyer for a match-machine, a section comprising the rack-bars B having lugs C c, combined with the composite supporting-bars for the matches each having 40 flanges D', apertures L and slots d into which the rack-bars fit and bar N having loops I extending through the apertures, the flanges D' resting against the lugs C of the said rack-bars, and a spring G pressing against one of the composite supporting-bars and looped over the lugs c of the rack-bars for holding them in the slots d of the said supporting-bars.

In testimony of which invention I have hereunto set my hand.
